Patented Aug. 3, 1915.

UNITED STATES PATENT OFFICE.

ALEXANDER E. SQUYARS AND WILLIAM T. HEFNER, OF STATESBORO, GEORGIA,
ASSIGNORS, BY MESNE ASSIGNMENTS, TO WILLIAM T. HEFNER.

MOP.

1,148,869.

Specification of Letters Patent.

Patented Aug. 3, 1915.

Application filed September 9, 1914. Serial No. 860,957.

To all whom it may concern:

Be it known that we, ALEXANDER E. SQUYARS and WILLIAM T. HEFNER, citizens of the United States, residing at Statesboro, in the county of Bulloch, State of Georgia, have invented certain new and useful Improvements in Mops; and we do hereby declare the following to be a full, clear, and exact description of the invention, such as 10 will enable others skilled in the art to which it appertains to make and use the same.

This invention relates to improvements in mops, and more particularly to a novel form of mop head designed for the reception 15 of bristles, felt or other material adapted for mopping purposes.

An object of the invention resides in the provision of an article of the above character, in which the various parts may be 20 readily manipulated to effect the clamping or removal of the mopping material.

A further object of the invention is to provide a mop head which is extremely 25 strong and durable in construction, highly efficient in use and one which comprises but few simple parts whereby the cost of production will be reduced to the minimum.

With the above and other objects of similar nature in view the invention consists in 30 the construction, combination and arrangement of parts set forth in and falling within the scope of the appended claim.

In the drawings: Figure 1 is a front elevation of a mop constructed in accordance 35 with the invention. Fig. 2 is an end view thereof. Fig. 3 is a longitudinal sectional view through the device, and Fig. 4 is a perspective view with the parts in open position.

40 Referring now more particularly to the drawing, the mop comprises a head 10, handle 11, and mopping material 12, the latter in this instance being illustrated as felt or other like material.

45 In detail, the head 10 consists of a bar 13 the under face of which is concaved as at 14, said bar being provided intermediate its ends with a threaded opening 15 in which is engaged a thumb screw 16 for detachably 50 securing the handle 11 to the bar. It will be noted that each end of the bar 13 is reduced transversely as at 17 and that normally engaged in these reduced portions are the looped ends 18, 18' of a wire frame 19,

said frame including spaced parallel bars 55 20 which constitute one element of the securing means for the mop.

At one end of the bar 13 there is provided a plate 21, which is held in place by screws 22 or other suitable means and projects above 60 and below the reduced portion 17, the upper extension thereof being provided with an opening 23 through which is passed a pin 24 for hingedly connecting the looped end 18 of the frame 19 to the bar. The lower 65 extension of this plate 21 is provided with an opening 25 in which is engaged one end of a clamping rod 26, said rod being co-extensive with and disposed below the bar 13 and adjustably supported at its opposite end 70 in an eye bolt 27 loosely inserted through said bar. It will be observed that the rod 26 is provided adjacent its ends with notch 28 which is engaged respectively in the opening 25 and eye bolt 27 and serves to 75 prevent longitudinal displacement of the rod.

It will further be noted that there is provided on the bar 13 a latch 29 having formed therein a slot 30 through which is passed 80 the bolt 27, said latch being slidable into or out of locking engagement with the looped end 18' of the frame 19 and held in such position by means of the thumb nut 31.

In applying a mop to the head 10, the 85 parts of the latter are moved to the position shown in Fig. 4 and the mop arranged between the bar 13 and the clamping rod 26. The frame 19 is then swung downwardly on its pivot to compress the mop adjacent its 90 intermediate portions between the rods 20 of the frame and bring the looped end 18' thereof against the reduced end 17, of the bar. The latch member 29 is then slid forwardly on the bolt 27 and the thumb nut 31 95 tightened to clamp the mop between the bar 13 and the rod 26 and securely lock the frame 19 in position.

What is claimed is:

A mop head comprising a bar, a frame 100 having one end hingedly connected with said bar and its other end detachably engaged therewith, a plate on one end of the bar provided with an opening, a rod disposed below said bar with one end engaged 105 in said opening, a bolt loosely inserted through said bar and terminating in an eye to receive the other end of said rod, a

latch member slidably engaged on said bolt and adapted to lock the free end of said frame to the bar, and means threadedly engaged with said bolt whereby tightening thereof serves to clamp a mop between said rod and bar and secure the latch in locking position.

In testimony whereof, we affix our signatures, in the presence of two witnesses.

ALEXANDER E. SQUYARS.

WILLIAM T. HEFNER.

Witnesses:

Z. R. CONNELL,

W. W. DeLOVCH.
